UNITED STATES PATENT OFFICE.

ARTHUR E. ROPE, OF BROOKLYN, NEW YORK.

ASSOCIATION VANITY BOX.

Application filed March 23, 1922. Serial No. 546,087.

To all whom it may concern:

Be it known that I, ARTHUR E. ROPE, a citizen of the United States, and a resident of the city of New York, borough of Brooklyn, in the county of Kings and State of New York, have invented a new and Improved Association Vanity Box, of which the following is a full, clear, and exact description.

10 This invention relates to improvements in association vanity boxes, an object of the invention being to provide a neat and attractive assemblage of containers in which articles and material may be supported 15 which a lady may need, and which will facilitate the use of the contents by reason of the convenience of the device.

A further object is to provide a device of the character described in which a plurality 20 of separate containers are rigidly secured in a neat and ornamental assemblage, and which will preferably be, in its entirety, an extremely small and compact device easily supported on the finger of the user.

25 With these and other objects in view the invention consists in certain novel features of construction, and combinations and arrangements of parts as will be more fully hereinafter described and pointed out in the 30 claims.

In the accompanying drawings—

Figure 1 is a perspective view illustrating my improved association vanity box.

Figure 2 is a view in section on the staggered line 2—2 of Figure 1.

Figure 3 is a view in section on the staggered line 3—3 of Figure 1.

The several views above described illustrate my invention in exaggerated form, and it is the purpose of my invention to provide an extremely small and compact device, and the illustration is exaggerated for reasons of clearness only. It is, of course, to be understood that the invention is not limited 45 to any particular size, but will present, in my judgment, a stronger appeal if made extremely smaller.

In constructing my improved association vanity box I provide a plurality of containers 50 1, 2, 3, 4 and 5 respectively, and while I have illustrated my device as containing five of such receptacles, it is obvious that I do not limit my invention to the exact number or to the exact size and proportion of these 55 containers. However, I preferably form the container 1 of materially greater diameter

than the other containers and divide the same by a partition 6 into two compartments 7 and 8 respectively.

The containers are provided with removable covers 9, and as the container 1 comprises two compartments, it is provided with covers 9 at its respective ends, and all of these covers may have screw threaded engagement with their several compartments, 60 as shown, or may be connected and held in any approved manner. The containers are all preferably of the same length and are connected by walls or webs 10, which may be cast integral with the containers or secured thereto in any approved manner.

Plates 12 are fitted within the spaces between the several containers and fit against the webs 10, so as to give a neat and attractive finish to the assemblage. Certain of 75 the containers are preferably provided with eyes 13 for the reception of the ends of a chain or other similar device 14, so that the latter may be conveniently used as a support for the vanity box.

The containers 3 and 4 preferably receive bottles 15 and 16 respectively, one of which may constitute a cologne or scent bottle, and the other may contain smelling salts. The containers 2 and 5 are adapted to enclose 80 an eyebrow pencil 17 and lipstick 18 respectively, and this pencil and lipstick are preferably held within the covers 9, so that when the covers 9 are removed, they will act as supports for the eyebrow pencil and lipstick respectively and facilitate their use 85 without soiling the fingers.

The covers 9 of container 1 each preferably support mirrors 19 in their outer faces and powder puffs 20 at their inner faces. 95 The compartment 7 preferably contains face powder 22, while in the compartment 8 rouge 23 is preferably located, so that by the removal of the proper cover, the use of the proper puff or applying device, either 100 face powder or rouge, may be conveniently used.

While I have indicated a preferable arrangement of contents for the several containers, it is obvious that these may be 105 varied without departing from the invention, and, as a matter of fact, the owner of the vanity box may decide to use various contents, as he may please.

It will be noted that the several containers 110 are arranged in a somewhat circular series so that their outer surfaces conform within

the arc of a circle, thus making the device a very compact one and may be made very small and light, so that it can be conveniently carried on the finger of the user. The 5 invention, of course, is not limited to the material employed as the device may be made of metal, celluloid, or any other material adapted for the purpose.

Various slight changes might be made in 10 the general form and arrangement of the parts described without departing from the invention, and hence I do not limit myself to the precise details set forth, but consider myself at liberty to make such changes and 15 alterations as fairly fall within the spirit and scope of the appended claims.

I claim:

1. A device of the character described, comprising a plurality of independent containers, webs fixedly connecting the containers, and plates at the ends of the webs and spaced from the ends of the containers.

2. A device of the character described, comprising a plurality of assembled containers, one of said containers having a partition therein dividing it into two compartments, covers on all of said containers and

on both ends of the container having a partition therein, applying devices fixed to the inner faces of the last-mentioned covers, 30 and a mirror mounted in the top cover of one of the containers.

3. A device of the character described, comprising a plurality of containers, webs connecting the containers together to form 35 a unitary structure, and plates seated on the webs forming a box-like structure.

4. A device of the class described, comprising a plurality of containers positioned along the circumference of a circle and 40 spaced from one another, webs extending between the containers, and plates mounted on the webs forming a box-like structure carrying the containers.

5. A device of the character described, comprising a plurality of independent containers, all of said containers being of the same height with their ends in alinement, said containers being of various varying sizes, removable covers on the containers, 50 and webs connecting the containers to form a unitary structure.

ARTHUR E. ROPE.
